UNITED STATES PATENT OFFICE.

LESLIE E. SUNDERLAND, OF JOLIET, ILLINOIS.

WIRE-STRETCHER.

SPECIFICATION forming part of Letters Patent No. 291,955, dated January 15, 1884.

Application filed May 21, 1883. (No model.)

To all whom it may concern.

Be it known that I, LESLIE E. SUNDERLAND, a citizen of the United States of America, residing at Joliet, in the county of Will and State of Illinois, have invented certain new and useful Improvements in Wire-Stretchers, of which the following is a specification, reference being had therein to the accompanying drawings.

10 Figure 1 is a plan view on the top; Fig. 2, a side view; Fig. 3, a central cross-section of the windlass; Fig. 4, a side view of the lower end of the operating-lever; Fig. 5, a plan view on the top of the windlass; Fig. 6, a view of the 15 stretching-rope; Fig. 7, a side view of the lower end of the operating-lever, showing a spring-pawl attached to its side; and Fig. 8, is a perspective view.

This device is for stretching cords or wires, 20 and is intended more particularly to be used to stretch fence-wires; and it relates to certain improvements therein, which I will now more particularly explain by reference to the drawings.

25 Referring to the drawings, *a* represents the stock or body of the device, intended to be made of cast metal, and having one end terminating in a fork, between the extremities of which is located a drum or windlass, *a'*, upon 30 which the rope *d* is wound. The other end of the stock or body *a* is provided with a clutch, to grasp and hold the fence-wire *W*, as shown in Fig. 1. This clutch consists of a dog, *D*², held or pivoted on the frame *a* by the rivet *D'* and 35 washer *D*, so that it may revolve. One side or edge of the dog *D*² is serrated or toothed, and projects like a cam against the upturned serrated face *m*, between which and it the wire *W* is grasped. The cap *n* prevents the wire 40 *W* from falling out. The drum or windlass *a'* is provided at one end with the head *a'*, to prevent the rope *d* from running off the drum, and at the other end with the ratchet *R*, serving the same purpose, both head and ratchet being integral with drum *a'*. The shaft *S* passes 45 loosely through the frame *a* and drum *a'*, so that it can be removed for the purpose herein-after named. The apertures through the two heads of the drum *a'* are of the same diameter 50 as the shaft *S*, while the inner diameter of the

drum *a'* is considerably greater than that of the shaft *S*, as shown in Figs. 1 and 3, which is for the purpose of securing one end of the rope *d* to the drum. The rope *d* is attached to the drum by first removing the shaft *S* and inserting the end of the rope through a hole in the side of the drum, as shown at *a*, Fig. 3. The shaft *S* is then driven in so that the end of the rope is held tightly between the shaft *S* and the inner wall of the drum, as shown in said Fig. 3. By this means of fastening, no knot is required on that end of the rope, and the surface of the drum is left free to wind the rope on.

The apparatus for rotating the drum to wind up the rope consists of the lever *C*, the lower 65 end of which is pivoted on the shaft *S*, next outside the ratchet *R* by the long slot *B*. (Shown more particularly in Figs. 2 and 4.) The side of the lever *C* next the ratchet *R* has an integral projection, *P*, acting as a pawl to 70 engage the teeth of the ratchet *R*. A reciprocating motion backward and forward of the lever *C* will drive the ratchet forward, where it is held by the detent-pawl *P'* until the lever *C* can return for a new hold on the ratchet *R*. 75 The slot *B* permits the projection *P* on the lever *C* to slide backward over the ratchet-teeth. If desired, a spring click or pawl might be attached to the side of lever *C*, as shown in Fig. 7, and the slot *B* dispensed with, which might 80 answer the same purpose; but the construction first described and shown in Figs. 1, 2, and 4 is preferred. The lever *C* is hollow at its outer end to receive an extension-handle for greater leverage. In case a chain is desired in place 85 of the rope, the drum *R* may be constructed with a serpentine annular channel, *g*, as shown in Fig. 5, to receive the chain *Z*, the form of the channel *g* serving to hold the chain frictionally. The outer end of the rope *d* is intended to be provided with a clutch for grasping the wire *W*, as shown in Fig. 1. In case 90 it is desired to pull the two broken ends of a fence-wire together, so that they may be reunited, as shown in Fig. 8, the rope *d* is first 95 unwound from the drum, and the clutch on its outer end made fast to one loose end of wire *W*, while the other loose end of said wire is held by the clutch on the frame *a*, as shown in Figs. 1 and 8. The lever *C* is then operated, 100

as before stated, until the two ends of the wire are drawn near enough together to be united. A release of the pawl C' from the ratchet R will permit the drum a' to turn backward and 5 unwind the rope d from the drum a'.

When it is desired merely to stretch the wires W taut by a pull on one end, so that they can be attached to the posts, the rope d may be hooked around a convenient post or tree or o any object by means of the hook q, (shown in Fig. 6,) the hook q forming the knot to hold the rope attached to the clutch at that end.

Having thus described my invention, what I claim as new, and desire to secure by Letters 5 Patent, is as follows, to wit:

1. In the wire-stretcher described, the combination of the body or frame a, provided with a suitable clutch at one end to grasp and hold the wire W, slotted lever C, having the pawl P, and journaled by its slot on the shaft S, drum-ratchet R, drum a', having an annular

inner chamber between its ends surrounding the removable shaft S, for the reception of the end of the rope d through a hole in the side of said drum, removable shaft S, adapted to 25 be withdrawn and driven through said drum a', to retain the end of said rope within said drum between its inner walls and said shaft S, detent-pawl P', having the extended handle C', and rope d, provided with a suitable clutch or 30 hook, q, at its outer end, all arranged to operate as and for the purpose set forth.

2. In a wire-stretcher, the removable shaft S, in combination with the drum a', having an inner chamber larger than said shaft and surrounding said shaft, for the reception of the rope d between said shaft and the inner walls of said drum, as and for the purpose set forth.

LESLIE E. SUNDERLAND.
